UNITED STATES PATENT OFFICE

149,462

DESIGN FOR A ROSARY

Catherine Vandernoot, New York, N. Y.

Application April 6, 1946, Serial No. 128,344

Term of patent 14 years

(Cl. D45—16)

To all whom it may concern:

Be it known that I, Catherine Vandernoot, a citizen of the United States of America, residing at New York, county and State of New York, have invented a new, original, and ornamental Design for a Rosary, of which the following is a specification, reference being made to the accompanying drawing, forming a part thereof.

Fig. 1 is a view partly in perspective of a rosary embodying my new design and showing the crucifix element thereof in open position, and

Fig. 2 is a fragmentary perspective view of the rosary showing the crucifix element in closed position.

The beads and medallions shown in full lines are repeated throughout the length of the rosary as indicated by the broken line showing.

The appearance of the opposite sides of the beads and the appearance of the opposite sides of the medallions correspond to the respective sides of the beads and medallions as shown in full lines.

I claim:

The ornamental design for a rosary, substantially as shown and described.

CATHERINE VANDERNOOT.
